United States Patent [19]

Bergström et al.

[11] Patent Number: Des. 277,831

[45] Date of Patent: ** Mar. 5, 1985

[54] TRANSMITTER FOR IN-LINE
CONNECTION BY MEASURING OF FLUID
CONSISTENCY

[76] Inventors: Pär H. S. Bergström, Vassvägen 5H,
S-141 39 Huddinge; Roland E.
Jelvestam, Björnidegränd 29, S-163
64 Vällingby, both of Sweden

[**] Term: 14 Years

[21] Appl. No.: 378,318

[22] Filed: May 14, 1982

[30] Foreign Application Priority Data

Nov. 25, 1981 [SE] Sweden 81-2760

[57] CLAIM

The ornamental design for a transmitter for in-line connection by measuring of fluid consistency, as shown and described.

DESCRIPTION

FIG. 1 is a front perspective view of a transmitter for in-line connection by measuring of fluid consistency showing our new design;

FIG. 2 is a side perspective view thereof, the other side being a mirror image;

FIG. 3 is a top plan view thereof.

FIG. 1

FIG. 2

FIG. 3
